(57) **CLAIM**

The ornamental design for clock, as shown and described.

DESCRIPTION

FIG. 1 is a front elevation view of the clock of the invention;

FIG. 2 is a top view of the clock;

FIG. 3 is a bottom view of the clock;

FIG. 4 is a side view of FIG. 1 showing an optionally extendable holding bracket for standing the clock on a flat surface as opposed to hanging it on a wall;

FIG. 5 is a rear elevation view of the clock; and,

FIG. 6 is a perspective view of the clock.

The numerals of the clock display are provided by an electro-luminescent display on a glass substrate.

The broken line showing of an optionally extendable holding bracket is for illustrative purposes only and forms no part of the claimed design.
